UNITED STATES PATENT OFFICE.

PERCY JENNER, OF WHEELING, WEST VIRGINIA, ASSIGNOR TO WARWICK CHINA COMPANY, OF WHEELING, WEST VIRGINIA.

DESIGN FOR A PLATE.

48,225.

Specification for Design.

Patented Nov. 30, 1915.

Application filed October 4, 1915. Serial No. 54,093. Term of patent 7 years.

To all whom it may concern:

Be it known that I, **PERCY JENNER**, a subject of the King of England, residing at Wheeling, in the county of Ohio and State of West Virginia, have invented a new, original, and ornamental Design for Plates, of which the following is a specification, reference being had to the accompanying drawing, forming part thereof.

The drawing illustrates a plan view of the plate showing my new design.

I claim:

The ornamental design for a plate, as shown.

PERCY JENNER.
